[57] **CLAIM**

The ornamental design for a box for a roll of film, as
shown and described.

DESCRIPTION

FIG. 1 is a top perspective view of a box for a roll of
film showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a top plan view shown in unfolded condition;

FIG. 9 is a top perspective view of a second modified
embodiment;

FIG. 10 is a front elevational view thereof;

FIG. 11 is a rear elevational view thereof;

FIG. 12 is a top plan view thereof;

FIG. 13 is a bottom plan view thereof;

FIG. 14 is a left side elevational view thereof;

FIG. 15 is a right side elevational view thereof;

FIG. 16 is a top plan view shown in an unfolded condition;

FIG. 17 is a top perspective view of a third modified
embodiment;

FIG. 18 is a front elevational view thereof;

FIG. 19 is a rear elevational view thereof;

FIG. 20 is a top plan view thereof;

FIG. 21 is a bottom plan view thereof;

FIG. 22 is a left side elevational view thereof;

FIG. 23 is a right side elevational view thereof;

FIG. 24 is a top plan view shown in an unfolded condition;

FIG. 25 is a top perspective view of a fourth modified
embodiment;

FIG. 26 is a front elevational view thereof;

FIG. 27 is a rear elevational view thereof;

FIG. 28 is a top plan view thereof;

FIG. 29 is a bottom plan view thereof;

FIG. 30 is a left side elevational view thereof;

FIG. 31 is a right side elevational view thereof; and

FIG. 32 is a top plan view shown in an unfolded condition.

The stippling represents a color contrast.

The continuous diagonal line pattern shown in FIGS. 9,
10, 12, 14-16, 25, 26, 28 and 30-32 is a feature of the
design and does not represent shading.
